Primary Examiner — Richard Kearney*Assistant Examiner* — David Weir(74) *Attorney, Agent, or Firm* — Dickinson Wright PLLC; Andrew D. Dorisio(57) **CLAIM**

The ornamental design for a conveyor module as shown and described.

DESCRIPTION

FIG. 1 is a top perspective view of the conveyor module showing our new design;

FIG. 2 is a bottom perspective view thereof;

FIG. 3 is a top view thereof;

FIG. 4 is a front view thereof;

FIG. 5 is a bottom view thereof;

FIG. 6 is a rear view thereof;

FIG. 7 is a right side view thereof; and,

FIG. 8 is a right side view of FIG. 2.

The broken lines in the figures are for the purpose of depicting portions of the conveyor module that form no part of the claimed design.

1 Claim, 4 Drawing Sheets(56)
